Primary Examiner — Richelle G Shelton(74) *Attorney, Agent, or Firm* — Womble Bond Dickinson (US) LLP(57) **CLAIM**

The ornamental design for a fluid conduit transfer tip, as shown and described.

DESCRIPTION

FIG. 1 is a left side view of my new design, the right side view being a mirror image thereof;

FIG. 2 is a front view thereof;

FIG. 3 is a rear view thereof;

FIG. 4 is a top view thereof, the bottom view being a mirror image thereof; and,

FIG. 5 is a front left perspective view thereof.

The jagged break lines and brackets in FIGS. 1, 4 and 5 represent that the length of the broken portion is not claimed.

1 Claim, 1 Drawing Sheet(56)
